UNITED STATES PATENT OFFICE.

BRINTON MILLER, OF GERMAN VALLEY, ILLINOIS.

SIGNAL-SWITCH.

1,159,521.

Specification of Letters Patent.

Patented Nov. 9, 1915.

Application filed October 27, 1914. Serial No. 868,892.

To all whom it may concern:

Be it known that I, BRINTON MILLER, a citizen of the United States, residing at German Valley, in the county of Stephenson and State of Illinois, have invented new and useful Improvements in Signal-Switches, of which the following is a specification.

This invention relates to railway switch controlled signals and has for its primary object the provision of a signal system whereby a visible signal will be given at a remote point to indicate whether the switch is open or closed.

Another object of the invention is the provision of a signal system wherein the circuit closer will be positive in its operation irrespective of the long period of idleness, such as is experienced on branch lines.

A further object of the invention is the provision of a signal system wherein the circuit is closed through a switch that is operated by a reciprocating bar that receives its motion from the railway switch signal post.

A still further object of the invention is the provision of a signal system wherein the pressure between the contacts of the circuit closer can be increased to insure a perfect electrical contact.

The invention in the preferred form in detail will be described in the following specification, reference being had particularly to the accompanying drawings, in which:

Figure 1 is a diagrammatic view of a track-way showing the position of my improved system with relation to the switch points of a branch line. Fig. 2 is a top plan view of the circuit closer showing the casing in section. Fig. 3 is a section on line 3—3 of Fig. 2. Fig. 4 is a detail view of one contact. Fig. 5 is a vertical section on line 5—5 of Fig. 2. Fig. 6 is a section 45 through the base of a semaphore showing the actuating mechanism therefor. Fig. 7 is a view similar to Fig. 2 showing the circuit closer in closed position.

Referring to the drawings, and more particularly to the diagrammatic view, Fig. 1, the numeral 1 designates the rails of a main line, while the numeral 2 designates the switch points of a side line. Positioned beside the main line 1 and adjacent one of the switch points 2 is a switch dwarf signal 3 that is controlled by the switch point

through a link 4. Rigidly fastened to the vertical post 5 of the dwarf signal 3 is a crank 6 having a pin and slot connection 7 with a horizontally disposed bar 8 composed of insulating material. Embedded in opposite sides of the bar 8 are contact strips 9 and 10 to which are connected terminals of a circuit 11. Disposed on opposite sides of the bar 8 are pivotally mounted contacts 12 constructed so as to have a rearwardly extending tapering curved portion 13. The forward end of each of the contacts is provided with a recess 14 and an apertured lug 15 adapted to have pivotally connected thereto lugs 16 carried by the head 17. Interposed between the head 17 which forms a portion of the contact 12 and the body of the contact, is a coil spring 18, the tension of which is utilized for forcing the head of each contact toward the other so as to contact with the opposite sides of the bar 8. The free end of the bar 8 is beveled as shown at 18' so that when the bar is moved forwardly, the tapering portion of the contacts are thrown outwardly, thus bringing the opposite ends of the contact into closer engagement with the sides of the bar, this action being yieldably taken up by the coil springs 18 until the shoulders 19 of the heads come into contact with the shoulders 20 of the body of the contacts. The circuit 11 has in series therewith a motor 21 having upon its armature shaft a worm 22 adapted to engage the worm wheel 23 rigidly mounted upon a shaft 24 which passes transversely through the base of the semaphore 25. Positioned on the shaft 24 in spaced relation with the worm wheel 23, is a crank disk 26 having pivotally connected thereto the vertical rod 27 which operates the semaphore blade 28 when the motor is operated through the closing of the circuit closer.

The operation is as follows: When the switch point is thrown so that a train can take the siding, a rotary motion is given to the vertical shaft 5, this rotary motion being converted into a reciprocatory motion through the crank 6 and rod 8. The rod 8 in sliding forwardly forces the tail ends of the pivoted contacts outwardly for bringing the heads 15 inwardly for increasing their frictional contact between the contact strips 9 and 10. The current in the circuit 11 passes through the contact strip 9 through the pivoted contact, and through its support to the opposite pivoted contact and then out

by way of the contact strip 10 so as to energize the motor 21 which throws the semaphore to a danger position.

From the foregoing description taken in connection with the accompanying drawings, the advantages of the construction and of the method of operation will be readily apparent to those skilled in the art to which the invention relates, and while I have described the principle of operation of the invention, together with the device which I now consider to be the best embodiment thereof, I desire to have it understood that the device shown is merely illustrative and that such changes may be made when desired as are within the scope of the claims.

What I claim is:

1. A circuit closer comprising a casing a pair of contacts pivotally mounted therein and electrically connected together, each of said contacts being formed to have a hinged head portion and a rearwardly curved tapering tail portion, a bar of insulating material slidably mounted between the heads of the

contacts and having a wedging action with the tail portions thereof, electrical contact strips embedded in said bar, and means for reciprocating said bar.

2. A circuit closer comprising a casing, a pair of contacts pivotally mounted therein and electrically connected together, each of said contacts being formed to have a hinged head portion and a rearwardly curved tapering tail portion, a bar of insulation slidable between the head portions of said contacts and having a wedging action with the tail portions thereof whereby the friction between the head portions and the bar may be increased, a spring interposed between said head and tail portion, electrical contact strips embedded in said bar, and means for reciprocating said bar.

In testimony whereof I, affix my signature in presence of two witnesses.

BRINTON MILLER.
